UNITED STATES PATENT OFFICE.

JULIUS HILDER, OF NEW YORK, N. Y.

DESIGN FOR A BODICE-BELT ORNAMENT.

SPECIFICATION forming part of Design No. 33,210, dated September 18, 1900.

Application filed June 11, 1900. Serial No. 19,067. Term of patent 3½ years.

To all whom it may concern:

Be it known that I, JULIUS HILDER, a citizen of the United States, residing in New York city, borough of Manhattan, in the State of New York, have invented and produced a new and original Design for a Bodice-Belt Ornament, of which the following is a specification, reference being had to the accompanying drawings, forming part hereof, wherein—

Figure 1 is a face view of a bodice-belt ornament embodying my design, and Fig. 2 is a cross-section thereof on the line 22 in Fig. 1.

The leading and material feature of my design consists in the configuration of a bodice-belt ornament wherein the sides are concave and the edges of the end portions beyond the latter extend outwardly and converge toward each other, the central portion of the attachment being correspondingly shaped, forming a border around the body.

In the drawings, the letter A indicates the bodice-belt ornament, the opposite concave or inwardly-curved sides being indicated at a, and the edges of the end portions which converge in an outward direction toward each other beyond the curved sides are denoted by a'. The central portion B of the ornament is raised and has curved sides b and converging end portions b', corresponding to the sides a and the edges a', respectively, forming a border C around the central portion B.

I claim—

The design for a bodice-belt ornament, as herein shown and described.

JULIUS HILDER.
